(57) **CLAIM**

The ornamental design for a beverage container lid, as shown and described.

DESCRIPTION

FIG. 1 is a perspective view of a beverage container lid showing my new design;

FIG. 2 is a left side view thereof;

FIG. 3 is a right side view thereof;

FIG. 4 is a front view of thereof;

FIG. 5 is a rear view thereof;

FIG. 6, is a top view thereof; and,

FIG. 7 is a bottom view thereof.

The broken lines in the drawing views represent unclaimed portions of a beverage container lid, which are included for the purpose of illustrating unclaimed environment only, and form no part of the claimed design.
